UNITED STATES PATENT OFFICE.

MERRILL G. BENJAMIN, OF POLAND, OHIO, ASSIGNOR TO THE BENJAMIN ENGINEERING COMPANY, OF CLEVELAND, OHIO, A CORPORATION OF OHIO.

GOVERNOR.

Application filed March 27, 1920. Serial No. 369,297.

To all whom it may concern:

Be it known that I, MERRILL G. BENJAMIN, a citizen of the United States, residing at Poland, in the county of Mahoning and 5 State of Ohio, have invented a new and useful Improvement in Governors, of which the following is a full, clear, and exact description.

The present invention relates to governors, 10 and more particularly to a governing means for maintaining a machine at a uniform speed, but which uniform speed is adjusted to meet certain conditions. Such governing means is adapted for controlling the 15 speed of engines and turbines driving such machines as gas exhausters and boosters, turbo blowers, boiler feed pumps, forced and induced draft fans for boiler furnaces, or any other machine where it is desirable 20 to control the speed of the machine by some function such as the pressure or volume of the fluid handled by the machine, the steam pressure in the boiler or other condition.

The invention is illustrated as applied to 25 the governor of a turbine or engine driving a forced draft fan, supplying air to a steam boiler furnace, and in which the draft is controlled by the pressure of the steam in the boiler.

30 In the specific embodiment of the invention herein illustrated, the governing device consists of a speed governor which is operated by the fan engine and which tends to maintain it at a substantially uniform speed. 35 A master governor, the speed of which is controlled by the pressure of the steam in the boiler, cooperates with the speed, or auxiliary, governor so as to adjust the speed at which such auxiliary governor maintains 40 the fan engine.

In the illustrated embodiment of the invention, Figure 1 shows schematically the governing means as applied to a single boiler and Figure 2 shows the governing 45 means applied to a battery of boilers.

In the drawings, reference numeral 2 indicates a boiler. The boiler furnace 3 is supplied with air by a forced draft fan 4 driven by a fan engine 5 illustrated as a steam turbine supplied with steam from the boiler 2. 50 The speed of the turbine 5 is regulated in accordance with the steam pressure in the boiler 2 by the governing means now to be described. The regulator 10 is connected by a pipe 11 to the boiler header 12. The

regulator 10 is preferably one which has a graduated step by step movement, the arm 13 assuming a number of intermediate positions in accordance with the variations in the steam pressure. These regulators are 60 old and well known in the art. Examples of such regulators in the patent literature are the Spencer Patents No. 338,686 of March 23, 1886, and No. 479,854 of August 2, 1892. A number of such regulators are 65 on the market such as the Spencer regulator, the Mason regulator, etc., so that the construction of the regulator indicated in the drawing need not be described in detail as it is a structure well understood by those 70 skilled in this art.

Connected to the movable arm 13 of the regulator is the movable contact point 14 of a rheostat 15. The rheostat 15 is placed in the field 16 of a motor 17. The armature 75 of the motor 17 is connected directly across constant voltage feeder mains 18. The field 16 with its adjustable rheostat 15 is also connected across the feeder mains. The rheostat is connected with the regulator 10 so 80 that when the steam pressure in the boiler increases the resistance is cut out on the rheostat and the speed of the motor 17 is decreased. If the pressure in the boiler decreases, the regulator operates through the 85 rheostat to increase the speed of the motor 17.

Mounted to be driven by the motor 17 is the governor 20 which will be designated as the master governor. This governor is 90 indicated diagrammatically as the usual ball and spring governor having the weights or balls 21 and the restraining spring 22. The balls 21 are carried on links 23 which are attached to a fixed point 24 on the 95 shaft 25. The other ends of the links are attached to a sleeve 26, which slides on the shaft 25 moving to the left at an increase in speed of the motor 17.

Mounted on the shaft 30 of the blower 100 turbine 5 is a speed governor 31 which is preferably a duplicate of the master governor. This second governor may be designated for convenience as the auxiliary 105 governor. The auxiliary governor is connected to a movable sleeve 32 which is moved to the left as, shown in the drawing, by an increase in speed of the blower turbine.

It is to be understood that the governors 110 are shown merely diagrammatically and

that any approved specific governor construction may be used.

The governor 31 will tend to maintain the turbine 5 at a uniform speed. The master governor 20 is so connected with the auxiliary governor 31 that the master governor adjusts in accordance with the steam pressure, the speed at which the governor 31 holds the turbine. The connection between these two governors is illustrated as a link and lever connection between them and the valve 35 which controls the flow of steam to the turbine. The valve 35 is preferably a balanced valve and, as shown in the drawings, is opened to admit more steam when the valve rod 36 is moved to the left. The valve rod 36 is connected to the upper end of a lever 37, the lower end of which is connected to the sleeve 32 so as to be moved back and forth by the travel of the sleeve 32 along the shaft 30. The lever 37 has a floating fulcrum 40 where it is connected to a link 41 which is connected at 42 to the middle of a lever 43. The lever 43 has a fixed fulcrum 44 and is connected at its other end with the sleeve 26 of the master governor.

The operation of the mechanism is as follows:—The auxiliary governor 31 maintains the turbine 5 and forced draft fan 4 at a constant speed so long as the floating fulcrum 40 is not shifted in position. When, however, there is an increase in the steam pressure in the boiler, the regulator 10 operates through the motor 17 to decrease the speed of the master governor 20, thereby causing the sleeve 26 to move to the right, moving the floating fulcrum also to the right. This will adjust the speed at which the auxiliary governor 31 maintains the turbine 5, decreasing such speed. The auxiliary governor 31 will then maintain the speed of the turbine 5 uniform or constant at such reduced speed. Conversely, if the steam pressure in the boiler decreases, the master governor 20 will shift the floating fulcrum 40 so that the auxiliary governor 31 will maintain the turbine 5 and fan 4 at a constant but increased speed so as to increase the rate of combustion and bring the steam pressure up to normal.

The linkage mechanism is shown only diagrammatically and may be constructed in various ways, or may be modified from that indicated in the drawings. For example, instead of a balanced steam valve 35, the linkage may operate a pilot valve of a relay governor. The variable speed motor may be operated by means other than the rheostatic control. The master governor driven by an electric motor, as shown in the illustrated embodiment, might be replaced with some other device acting in conjunction with the speed governor to adjust in accordance with some function of the boiler,

the speed maintained by the speed governor. While the particular function of the boiler, which controls the master governor, is described as the steam pressure, other functions, such as the steam flow, may be employed for this purpose.

In the drawing, for the sake of simplicity, the control is shown as applied to a single auxiliary, namely the forced draft fan, of a single boiler. The invention may, however, be otherwise applied, for example, in controlling other auxiliaries, and for a battery of boilers, as shown in Fig. 2. It may be employed in the system shown in the copending application of Hess and Benjamin, Serial No. 292,954, filed April 26, 1919, when it is desired to drive any of the auxiliaries by steam instead of by electricity. For example, the forced draft fans of the Hess and Benjamin system may each be driven by a steam engine, in which case each steam engine would be provided with a speed and a master governor, with the master governor driven by an electric motor, the speed of which would be controlled by the variable speed motor-generator set of the Hess and Benjamin system. Many other modifications and changes may be made within the scope of the invention as defined in the following claims.

I claim:

1. The combination with a steam boiler, of an auxiliary machine, a steam engine for driving the auxiliary machine, a governor tending to maintain the engine speed substantially uniform, and electric means controlled in accordance with a function of the boiler for increasing or decreasing the speed at which the governor maintains the steam engine, substantially as described.

2. The combination with a steam boiler, of an auxiliary machine and means for driving it, a governor tending to maintain the speed of the auxiliary machine substantially uniform, an electric motor and means for controlling the speed of the motor in accordance with a function of the boiler, a master governor driven by the motor, and connections between the master governor and first governor whereby the substantially uniform speed of the auxiliary machine is adjusted to some other substantially uniform speed in accordance with the function of the boiler, substantially as described.

3. The combination with a steam boiler, of an auxiliary machine and its driving means, a centrifugal governor tending to maintain the speed of the auxiliary machine substantially uniform, a centrifugal master governor controlled in accordance with a function of the boiler, and connections between the two governors whereby the substantially uniform speed of the auxiliary machine is adjusted to some other substantially uniform speed in accordance with a

function of the boiler, substantially as described.

4. The combination with a steam boiler, of an auxiliary machine, a steam engine for driving the auxiliary machine, a governor for maintaining the speed of the steam engine substantially uniform, and an electrically driven master governor controlled in accordance with a function of the boiler 10 for adjusting the substantially uniform speed at which the first governor maintains the steam engine to some other substantially uniform speed in accordance with a function of the boiler, substantially as described.

15 5. The combination with a steam boiler, of an auxiliary machine, a steam engine for driving the auxiliary machine, a governor for maintaining the speed of the steam engine substantially uniform, means for manually adjusting the speed maintained by the 20 governor, and electric means for automatically adjusting the substantially uniform speed maintained by the governor to some other uniform speed in accordance with a function of the boiler, substantially as described.

25 6. The combination with a steam boiler and its furnace, of a draft fan, a steam engine for driving the fan, a governor for the steam engine for maintaining it at a substantially uniform speed, and electric means controlled by the steam pressure or demand for adjusting the substantially uniform speed at which the governor maintains the 30 steam engine to some other substantially uniform speed, substantially as described.

35 7. The combination with a steam boiler,

of an auxiliary machine, means for driving the auxiliary machine, a governor for maintaining the speed of the auxiliary machine 40 substantially uniform irrespective of the load, a power driven master governor controlled in accordance with a function of the boiler and having connections with the first governor for adjusting the substantially uniform speed at which it maintains the auxiliary machine to some other substantially uniform speed in accordance with the function of the boiler, substantially as described.

45 8. The combination with a battery of boilers, of auxiliary machines for the individual boilers, steam engines for driving the auxiliary machines, steam engine governors for maintaining the speeds of each of the auxiliary machines substantially uniform, 50 and means controlled by a function of the entire battery for adjusting the speeds of the individual machines in accordance with such function of the battery, substantially as described.

55 9. The combination with a battery of boilers, of auxiliary machines for the individual boilers, steam engines for driving the auxiliary machines, steam engine governors for maintaining the speeds of each of the auxiliary machines substantially uniform, 60 and electric means controlled in accordance with a function of the entire battery for adjusting the speeds of the auxiliary machines in accordance with such function, 65 substantially as described.

In testimony whereof, I have hereunto set my hand.

MERRILL G. BENJAMIN.
